IRONING MACHINE

Peter Eduard Geldhof, Syracuse, N. Y., assignor
to Easy Washing Machine Corporation, Syra-
cuse, N. Y., a corporation of Delaware

Application April 8, 1936, Serial No. 73,339

5 Claims. (Cl. 312—24)

My invention relates to ironing machines and, more particularly, to a novel combined ironing machine and table.

An object of my invention is to provide an ironing stand, together with ironing elements supported thereby, and a cover for enclosing the ironing elements, the cover when closed enabling the structure to be used as a table and when open enabling the use of the ironing elements.

10 Another object of my invention is the provision of a combined ironing machine and table having a box-like cover extending over and enclosing the ironing elements which may be moved to a position preferably at the rear of the ironing stand 15 well below the top level of the ironing elements where it is out of the way, leaving a clear space on all sides of the ironing elements. The ironing elements are thus readily accessible and the cover is in a position such that it does not serve to direct the heat generated by the ironing elements 20 toward the operator in front of the machine.

A further object of my invention is the provision of a combined ironing machine and table in which the ironing elements are pivotally supported inside the ironing stand in an inclined position and the cover overlies the ironing elements, the construction being such that opening of the cover and moving it to the rear of the ironing stand simultaneously raises the ironing elements 30 into a horizontal position to enable their operation.

Another object of my invention is the provision of springs secured to the ironing stand and operatively connected to the platform upon which the ironing elements are mounted which serve to aid the operator in raising the ironing elements to operative position.

Another object of my invention is the provision of equalizing means whereby when the cover is 40 raised the opposite sides of the cover and the linkage for raising the ironing elements are caused to move together.

45 My invention further contemplates the provision of a novel linkage arrangement for enabling movement of the cover from a position enclosing the ironing elements to a position at the rear of the ironing stand, whereby the cover is first moved upward so as to clear the ironing elements, and then rearward and downward in a predetermined arc to a position at the rear of the ironing stand well below the level of the ironing elements.

50 Other objects and advantages of my invention will be more apparent from the following description when taken in connection with the accompanying drawings, in which:

Figure 1 is a view showing the cover in a closed position and taken on the line A—A of Figure 3 when the cover of that figure is in a closed position and the ironing elements are in a lowered position.

5 Figure 2 is a view similar to Figure 1, showing the cover in the open position and taken on the line A—A of Figure 3.

Figure 3 is a view looking down upon the machine with the cover open and taken on the line 10 3—3 of Figure 2.

Figure 4 is a view taken on the line 4—4 of Figure 3, showing a portion of the platform bracket and the toggle for raising the platform.

Figure 5 is a view taken on the line 5—5 of Figure 2, showing a portion of the equalizing means.

Figure 6 is a view taken on the line 6—6 of Figure 2.

Figure 7 is a view taken on the line 7—7 of Figure 3, showing the bracket by which the elements 20 are secured to the ironing stand.

Figure 8 is a view taken on the line 8—8 of Figure 3.

Figure 9 is a view similar to Figure 1, showing a modification of my invention.

25 Figure 10 is a view similar to Figure 2, showing the cover of the modification of my invention in open position.

Figure 11 is a view taken on the line 11—11 of Figure 10.

Figure 12 is a view taken on the line 12—12 of Figure 10.

Figure 13 is a view taken on the line 13—13 of Figure 10.

35 The ironing machine of my invention comprises an ironing stand 11 which has suitable side walls 12, a rear wall 13 and a front 14. The ironing stand is provided with suitable legs 16 and the upper edges of the side walls of the ironing stand are bent inward and downward to form a ledge 40 17 extending completely around the perimeter of the top of the ironing stand and defining an opening into which the ironing elements are raised when they are moved to their operating position. A box-like cover, generally indicated by the numeral 18, extends over and encloses the ironing elements. The cover has depending side walls 19, a rear wall 21, a front wall 22 and a horizontal top wall 23, the perimeter of which is suitably reinforced forming a ledge 24. The cover 18 has 50 its lower edge beaded and resting upon the ledge 17 of the top of the ironing stand.

55 The ironing machine itself, generally indicated by the numeral 26, which comprises the usual heated ironing shoe and roll, together with the 55

controls and driving mechanism therefor, is supported on a platform 27.

Since the mechanism on both sides of the machine is the same, a description of one side will be sufficient although, with respect to each element described, it will be understood that there is a corresponding element on the opposite side of the machine. As most clearly shown in Figure 4, the platform has a bracket 28 extending downward from the platform. The platform bracket has a rearwardly extending portion 29 and an extension 31 which extends downward and rearward and is pivoted at 32 to a U-shaped bracket 33 fixed to the underside of the ledge 17 of the ironing stand.

The mechanism for raising the ironing elements when the cover is opened comprises an arm 34 which is U-shaped in cross section as shown in Figure 6. The arm 34 is pivoted at 36 to a U-shaped bracket 37 extending from the front wall of the cover 18. The U-shaped arm 34 is bent at 38 so that, as indicated in Figure 2, the upper surface 39 thereof will lie flush with the top level of the ironing stand and the bent portion 38 will extend upward and rearward to clear the rear corner of the ironing stand. A bracket 41, shown in Figure 7, is fixed to the inner side wall of the ironing stand in the manner shown in Figure 6 and the arm 34 is pivoted to this bracket at 42 by means of a stud 43 having a washer and nut 45 on the end thereof and which is fixed to the U-shaped arm 34. From the pivot point 42, the arm 34 extends downward, as viewed in Figure 1, and has formed at the end thereof a flat topped tail piece 44. The tail piece is provided with a sidewardly extending stop 46 which, when the cover is in the open position, as shown in Figure 8, engages the under side of the rebent portion of the ledge 17 of the ironing stand and limits the upward movement of the arm 34. At a point spaced from the end of the arm 34 is pivoted, as at 47, one link 48 of a toggle, the other link 49 of which is pivoted to the link 48 at 51 and to the bracket 28 at 52. As shown most clearly in Figure 3, the link 48 has an offset 53 to enable the link 48 to clear the arm 34 during movement of the mechanism.

A link 54 is pivotally connected at 55 to a bracket 57 mounted on the inside of the cover and to the ironing stand at 58. The link is pivoted to the ironing stand, as indicated in Figure 7, through the bracket 41. As viewed in Figure 1, the end of the link 54 toward the pivot 55 is curved to the right and then upward as indicated at 59 so that the link 54 will clear the rear corner of the ironing stand and lie between the legs of the U-shaped arm 34 when the cover is open. The purpose of the link 54 is to control the movement of the cover so that the cover, when it is manually moved from one position to another, is forced to move in a fixed predetermined path.

Means are provided for insuring that the linkage on one side of the ironing stand will move simultaneously with the linkage on the other side of the cover and so that the opposite sides of the cover will move together. Such means comprise, as shown in Figures 1, 2 and 6, a pinion 61 which is fitted on a flattened portion of a collar 62 which surrounds the stud 43. The pinion 61 is retained in position by a pair of guide plates 63 and the collar 62 is enlarged at 64 to space the arm 34 from the guide plate 63. The pinion 61 meshes with a segment gear 66 which is pivoted at 67 to the bracket 41. To the segment gear 66

is pivoted, at 68, a link 69 which is pivoted at 71 to a crank 72. The crank 72 is rigidly connected to a shaft 73 through a web connection with a tubular sleeve 75 which is pinned to the shaft. The sleeve 75 is supported in the bracket 41. The shaft 73, as shown in Figure 3, extends across the machine and is similarly connected to a corresponding crank 72 on the opposite side of the machine.

For the purpose of aiding the operator in manipulating the cover and in raising the ironing elements to their operating position, a spring 76 is provided which has one end rigidly secured at 74 to the ironing stand and the other end secured, at 76, to a depending and offset portion 77 of the platform bracket 28. An apron 78, extending across the machine and pivoted at 79 to the frame, serves as a stop member for the platform and has a curled lower edge 81 adapted to receive the lower end of the platform and support it in the inclined position. A plurality of springs 82, suitably supported beneath the ledge 17, normally urge the stop in an upward direction so that the stop member follows the platform, as shown in Figure 2, when the platform is moved upward.

When the machine is in the closed, inoperative position, shown in Figure 1, the top of the cover may conveniently be used as a table. When it is desired to use the structure as an ironing machine, the operator lifts on the front of the cover and moves it upward. By reason of the fact that the cover is pivoted to the ironing stand both by the arms 34 and by the links 54, the cover is constrained to move in a fixed predetermined path, which path of movement may be made such that the lower forward edge of the cover clears the ironing elements and such that the lower edge of the cover clears the back of the ironing stand. It will be particularly noted that the links 54 are pivoted to the ironing stand rearwardly of their pivot to the cover which forces the rear lower edge of the cover, during the initial opening movement of the cover, to move upward thereby insuring that the lower edge of the cover will clear the rear edge of the ironing stand.

The cross member or equalizing rod 73, together with its connections to the arms 34, insures that the operating mechanism on opposite sides of the machine will move together and that the opposite sides of the cover will move together should the operator, when opening the cover, lift upon only one side thereof. The equalizing rod thus distributes the force exerted by the operator and the weight of the ironing elements equally between the operating mechanism on opposite sides of the machine.

Movement of the cover from the closed to the open position simultaneously raises the platform together with the ironing elements up to their operating position. During the initial opening movement of the cover, the arm 34 pivots about the pivot point 42 and moves the link 46 of the toggle rearward. Further movement of the cover causes the pivot 47 to pass to the left of a line drawn between the pivot 42 and the pivot 52, whereupon the toggle will begin to straighten out. When the cover has been moved upward and rearward a distance sufficient to bring the toggle nearly to a straightened condition, the stop 84 on the link 49 engages the link 46 so that a rigid connection is formed between the arm 34 and the platform so that further movement of the cover raises the ironing elements. It will be particularly noted that during the initial opening move-

ment of the cover, the operator is not required to lift the ironing elements but merely the weight of the cover. The toggle formed by the links 46 and 49 may be made of such length that the load of the ironing elements is not picked up until the cover has passed its balanced position, that is, its position when if free to move of itself it would drop by gravity to open position. When the cover has passed its balanced position, the weight thereof aids the operator in lifting the ironing elements to their operating position. The operator is further aided in lifting the ironing elements by the springs 70 which exert a pull as soon as the platform starts to move.

15 In the modification of my invention shown in Figures 9 to 13, inclusive, I have illustrated a combined ironing machine and table of the same general construction as that shown in Figures 1 to 8, inclusive. In this modification, the ironing stand 86, the cover 81, the ironing elements 88, the platform 89 and depending bracket 91 are of essentially the same construction as in the machine shown in Figures 1 to 8, inclusive. The platform, as more clearly shown in Figure 13, 20 through a member 90 rigid with the platform, is pivoted at 95 to a bracket 90' on the ironing stand. It will be understood, although the elements on only one side of the machine will be described, that the parts described are duplicated on the 25 other side of the machine.

20 A U-shaped arm 92, pivoted at 93 to the cover by means of a bracket, as viewed in Figure 9, extends downward and is pivoted at 94 to a bracket 96 secured to the side wall of the ironing stand. The connection, as shown in Figure 11, is 30 formed by a stud 97 rigidly secured to the arm 92 and secured in pivotal relationship with the bracket 96. The elements are held in position by a washer and bolt 98. A toggle, comprising the 35 links 99 and 101, is connected at 102 and 103 respectively to the arm 92 and the bracket 91. A stop 104 on the link 101 forms, when the arm 92 has been rotated a predetermined distance, a rigid 40 connection between the arm 92 and the platform 45 whereby the ironing elements are raised into their operating position.

45 The arm 92 is provided with a gear segment 106 which meshes with a pinion 107. The pinion 107 lies between two guide plates 108 and is rigidly secured to a shaft 109 which extends across the 50 machine and is rigidly connected on the other side of the machine to a pinion similar to the pinion 107. The shaft 109 is loosely mounted in a bracket 110, a suitable bushing 111 being provided. The pinion 107 and the guide plates 108 55 are fixed to the shaft by means of web constructions formed in these members which fit into slots on the end of the shaft 109. The shaft 109, together with its connections to the arms 92, insures that the operating mechanism on one side 60 of the machine will move simultaneously with the operating mechanism on the other side and that the load will be equally distributed between the operating elements on opposite sides of the 65 machine.

65 A link 112, similar in shape to the link 54 of the first construction described, pivoted at 110' to the cover and at 115 to the stand through a bracket 115' secured to the stand, serves the 70 same function in the present modification as that link. The platform 89 is maintained in the position shown in Figure 9 by a stop 113 pivoted at 114 to the ironing stand, suitable spring means 75 being provided so that the stop 113, as shown in Figure 10, will follow the platform when the

platform is moved upward. A spring 117, threaded on a depending offset portion 118 of the bracket 91, is secured at 119 to the ironing stand. The spring 117 serves to aid the operator in lifting the ironing elements up into their operating position when the cover is moved to the position shown in Figure 10.

75 It is believed unnecessary to discuss in detail the operation of the ironing machine of this modification since the operation and advantages thereof are substantially the same as above described in connection with the structure of Figures 1 to 8, inclusive.

80 It will be apparent that while I have shown the preferred forms of my invention, various changes and modifications may be made in the form, arrangement and relationship of parts without departing from the spirit of the appended claims.

I claim:

1. In a combined ironing machine and table, 20 in combination, a supporting structure, a platform hinged along one edge of the supporting structure and extending in an inclined position within the supporting structure, ironing elements mounted on said platform and projecting above 25 the level of the supporting structure, a hollow box-like cover resting on the supporting structure and extending over and enclosing the ironing elements and forming with the supporting structure a table, means pivotally interconnecting 30 said cover, supporting structure and platform for enabling the cover to be manually moved upward over the ironing elements and downward to a position at the rear of the ironing stand below the top level of the ironing 35 elements, said movement of the cover simultaneously raising the platform about its pivotal connection with the supporting structure to bring the ironing elements into operable position, and means interconnecting said cover and supporting 40 structure for causing said cover to move in a fixed predetermined path during its movement.

2. In a combined ironing machine and table, 45 in combination, a supporting structure, a platform hinged along the rear edge of the supporting structure and extending in an inclined position within the supporting structure, ironing elements mounted on said platform and projecting above the level of the supporting structure, a hollow box-like cover resting on the supporting structure extending over and enclosing the ironing elements and forming with the supporting structure a table, means on each side of the supporting structure pivotally connecting said cover, supporting structure and platform for enabling the cover to be manually moved upward over the ironing elements rearward and downward to a position at the rear of the supporting structure below the top level of the ironing elements, said movement of the cover simultaneously raising the platform about its hinge connection with the supporting structure to bring the ironing elements into operable position, means on each side of the supporting structure interconnecting said cover and supporting structure for 50 causing the cover to move in a fixed predetermined path, and a rotatable element interconnecting one of said pairs of means for equally distributing the load of the ironing elements and the forces exerted by the operator on said cover 55

60 A link 112, similar in shape to the link 54 of the first construction described, pivoted at 110' to the cover and at 115 to the stand through a bracket 115' secured to the stand, serves the 65 same function in the present modification as that link. The platform 89 is maintained in the position shown in Figure 9 by a stop 113 pivoted at 70 75 75

3. In a combined ironing machine and table, in combination, a supporting structure, a platform hinged along one edge of the supporting structure and extending in an inclined position

within the supporting structure, ironing elements mounted on said platform and projecting above the level of the supporting structure, a hollow box-like cover resting on the supporting structure and extending over and enclosing the ironing elements and forming with the supporting structure a table, means interconnecting said cover, supporting structure and platform for enabling the cover to be manually moved upward over the ironing elements and downward to a position at the rear of the ironing stand below the top level of the ironing elements, said movement of the cover simultaneously raising the platform about its pivotal connection with the supporting structure to bring the ironing elements into operable position, said means including a pair of arms on opposite sides of the supporting structure and gears operated by said arms, means interconnecting said cover and supporting structure for causing said cover to move in a fixed predetermined path during its movement, and spring means interconnecting said platform and ironing stand to aid in raising the platform to a 10 horizontal position.

5. In a combined ironing machine and table, in combination, a supporting structure, a platform hinged along one edge of the supporting structure and extending in an inclined position within the supporting structure, ironing elements mounted on said platform and projecting above the level of the supporting structure, a hollow box-like cover resting on the supporting structure and extending over and enclosing the ironing elements and forming with the supporting structure a table, means interconnecting said cover, supporting structure and platform for enabling the cover to be manually moved upward 15 over the ironing elements and downward to a position at the rear of the ironing stand below the top level of the ironing elements, said movement of the cover simultaneously raising the plat-

form about its pivotal connection with the supporting structure to bring the ironing elements into operable position, said means including a pair of arms on opposite sides of the supporting structure and gears operated by said arms, means interconnecting said cover and supporting structure for causing said cover to move in a fixed predetermined path during its movement, and spring means interconnecting said platform and ironing stand to aid in raising the platform to a 10 horizontal position.

5. In a combined ironing machine and table, in combination, a supporting structure, a platform hinged along the rear edge of the supporting structure and extending in an inclined position within the supporting structure, ironing elements mounted on said platform and projecting above the level of the supporting structure, a cover resting on the supporting structure extending over the ironing elements and forming with the supporting structure a table, means including a pair of arms on opposite sides of the supporting structure and gears operated by said arms, means interconnecting said cover and supporting structure for causing said cover to move in a fixed predetermined path during its movement.

5. In a combined ironing machine and table, in combination, a supporting structure, a platform hinged along one edge of the supporting structure and extending in an inclined position within the supporting structure, ironing elements mounted on said platform and projecting above the level of the supporting structure, a hollow box-like cover resting on the supporting structure and extending over and enclosing the ironing elements and forming with the supporting structure a table, means interconnecting said cover, supporting structure and platform for enabling the cover to be manually moved upward over the ironing elements and downward to a position at the rear of the ironing stand below the top level of the ironing elements, said movement of the cover simultaneously raising the platform about its hinged connection to the supporting structure to substantially a horizontal position and simultaneously enabling movement of the cover to the rear of the supporting structure well below the level of the ironing elements, a pair of links pivoted to the cover and to the supporting structure for constraining the cover to move in a predetermined path during its movement, and spring means interconnecting said platform and supporting structure for aiding in raising the platform to a 20 horizontal position.

PETER EDUARD GELDHOF.
